(57) **CLAIM**

The ornamental design for a “computer,” as shown and described.

DESCRIPTION

FIG. 1 is a top, front and right side perspective view of a computer according to my design;
FIG. 2 is a front elevational view thereof;
FIG. 3 is a rear elevational view thereof;
FIG. 4 is a top plan view thereof;
FIG. 5 is a bottom plan view thereof;
FIG. 6 is a right side elevational view thereof;
FIG. 7 is a left side elevational view thereof;
FIG. 8 is a top, front and right side perspective view of the computer in a closed condition;
FIG. 9 is a front elevational view thereof;
FIG. 10 is a rear elevational view thereof;
FIG. 11 is a top plan view thereof;
FIG. 12 is a bottom plan view thereof;
FIG. 13 is a right side elevational view thereof; and,
FIG. 14 is a left side elevational view thereof.
